[57] CLAIM

The ornamental design for a wheel chock, as shown and described.

DESCRIPTION

FIG. 1 is a front perspective view of a wheel chock showing my new design;

FIG. 2 is a front elevational view of the embodiment shown in FIG. 1, with the rear elevational view being a mirror image of FIG. 8;

FIG. 3 is a top plan view of the embodiment shown in FIG.

1, taken in the direction of arrow 3—3 in FIG. 2;

FIG. 4 is a left side elevational view of the embodiment

shown in FIG. 1, taken in the direction of arrow 4—4 in FIG.

2;

FIG. 5 is a right side elevational view of the embodiment

shown in FIG. 1, taken in the direction of arrow 5—5 in FIG.

2; and,

FIG. 6 is a bottom plan view of the embodiment shown in

FIG. 1, taken in the direction of arrow 6—6 FIG. 2.
